ELECTRON DISCHARGE DEVICE

Isaac Shoenberg, London, Cabot Seaton Bull, Hillingdon, and Sidney Rodda, Enfield, England, assignors to Electric and Musical Industries Limited, Middlesex, England, a company of Great Britain

Original application July 27, 1934, Serial No. 737,192. Divided and this application June 1, 1935, Serial No. 24,482. Renewed June 12, 1937. In Great Britain August 2, 1933

23 Claims. (Cl. 250—27.5)

The present invention relates to electron discharge devices of the kind comprising a cathode, a control grid and an anode and, between the control grid and the anode, a screening electrode. It is known that when valves of this kind are operated with large anode voltage swings and with a fixed positive voltage on the screening electrode, secondary emission tends to occur from the anode to the screening grid when, in the course of its oscillation, the anode voltage falls more than a certain small amount below the fixed voltage of the screening electrode. For many purposes the flow of such secondary emission current from the anode to the screen is undesirable and proposals have been made to prevent it.

In one known arrangement a third grid, usually connected to the cathode, is arranged between the screening electrode and the anode.

It is the principal object of the present invention to provide an electron discharge device of the kind above referred to in which the flow of secondary emission current from the anode to the screening electrode can be prevented with the aid of an electrode located at least mainly clear of the electron stream between the cathode and the anode and in such position that when it is maintained at a low potential such for example as cathode potential, it can modify the electrostatic field in the space between the screening electrode and the anode, this modification being such that, even in the absence of electron flow between the cathode and the anode, the rate of change of potential gradient from the anode to the screening electrode is made positive or has

its otherwise positive value increased over substantially the whole anode surface when the anode potential is lower than that of the screening electrode, and in such a manner that under operating conditions with the control grid at cathode potential and the screening electrode at a normal operating potential the anode voltage-anode current characteristic exhibits no inflection. The space charge itself also modifies the electrostatic field in the space between the anode and the screening electrode and this modification together with that produced by the auxiliary electrode has been found sufficient, under operative conditions, to prevent the flow of secondary electrons from the anode to the screening electrode, even though that due to space charge alone may be insufficient.

Although in some forms of discharge devices according to the present invention the distortion of the electrostatic field produced by the auxil-

iary electrode may not be such as to produce an actual potential minimum in the space between the anode and the screen, in the absence of electron flow, over the whole range of working voltages and corresponding working anode currents, nevertheless the combined effect of the means for modifying the electrostatic field and the space charge is always to produce a combined potential minimum throughout the whole range of working anode voltages and corresponding working anode currents over which secondary emission to the screening electrode might take place. This is usually regarded as the range over which the anode voltage is less than the screen voltage.

According to the present invention a discharge device comprises a cathode surrounded by a control grid and a screening grid, the screening grid being surrounded in part by an anode and in part by an auxiliary electrode insulated from said anode, wherein said anode and said auxiliary electrode are each in a plurality of sections, the sections of the anode being interspersed with the sections of the auxiliary electrode.

Various forms of discharge devices which can be made to exhibit the feature of the present invention will be described hereinafter and the theory which is at present considered to explain the observed phenomena will be set forth. It is to be understood, however, that this theory may require modification in the light of further knowledge.

The invention will be described with reference to the accompanying drawings, in which

Figures 1, 6 and 7 are diagrammatic views in plan of certain forms of discharge devices according to the present invention.

Figures 2 to 5 are curve diagrams serving to explain certain characteristics of discharge devices according to the invention,

Figures 8, 9 and 12 are diagrammatic views in plan of further forms of devices according to the invention,

Figures 10 and 11 are diagrammatic views in elevation and plan, respectively, of a further form of the invention,

Figures 13, 14, 15 and 16 are views in side elevation, front elevation, sectional elevation and plan, respectively, of a preferred constructional embodiment of the invention,

Figure 17 is a perspective view of an anode of the device of Figures 13 to 16,

Figures 18 and 19 are perspective views showing methods of supporting anodes in arrangements according to the present invention, and

Figures 20, 21, 22 and 23 are views in eleva-

tion, sectional plan, sectional elevation and underside plan, respectively, of a second preferred constructional embodiment of the invention.

Like parts are indicated in the various figures 5 by the same references.

Referring to Figure 1, there is shown diagrammatically the electrode arrangement of one form of device according to the present invention. A cathode *a* is of rectangular cross-section and is 10 elongated (in a direction perpendicular to the paper). Two control grids *b*₁ and *b*₂ are arranged one on each side of the cathode *a* and are spaced therefrom by means of insulating strips *k*, one strip being arranged near one end of the 15 cathode and another near the opposite end. Thus the strips *k* are located substantially outside the electron stream. Two screening grids *c*₁ and *c*₂ are arranged outside the control grid and are spaced therefrom by means of further 20 insulators *k*. This assembly may be clamped together in any convenient way and mounted within in a casing *e* which constitutes an auxiliary electrode. This auxiliary electrode has portions *l* extending towards but not to any great extent into 25 the discharge space. Anodes *d*₁ and *d*₂ are provided as shown. It will be assumed for the present that the anodes *d*₁ and *d*₂ are electrically connected together and that the two grids *b*₁ and *b*₂ on the one hand and *c*₁ and *c*₂ on the 30 other hand are also connected together.

If the anodes *d*₁, *d*₂ be maintained at a positive potential relatively to the cathode *a* and if the screens *c*₁ and *c*₂ be maintained at a potential which is higher than the anode, the potential distribution in the space between each 35 anode section *d*₁ and *d*₂ and the corresponding screen section *c*₁ or *c*₂ along lines normal to the screen and anode will be somewhat as represented in Figure 2, where voltages are plotted as 40 ordinates against distances as abscissa. The position of the anode is represented by the line *D* and the position of the screen by the line *C*, the heights of these lines representing the potentials at the anode and screen respectively. 45 The dotted curve *g*₀ shows the distribution of potential along lines between the anode and screen approximately normal to these electrodes in the absence of electron flow and without the auxiliary electrodes. In the case of infinite plane 50 parallel anode and screen this curve *g*₀ is a straight line. In other cases it is curved somewhat as shown. Owing to the action of the auxiliary electrode including the portions *l* thereof, it will be seen that the distribution of potential 55 between the anode and screen represented by the curve *g* is such that

$$\frac{d^2V}{dx^2}$$

60 is made more positive proceeding from the anode to the screen, where *V* is the potential at any point and *x* is the distance of this point from the anode. That is to say the rate of change of the potential gradient is more positive, the potential gradient being of course

$$\frac{dV}{dx}$$

70 It will be seen also that the potential gradient in the neighbourhood of the anode is very small and for this reason very little further drop in potential in the anode-screen space is necessary to produce a potential minimum in the space as shown in Figure 3 where the curve *g* of Figure 2 75 is shown dotted and the curve *h* shows the effect

of a further drop in potential in the space. Such a further drop can of course be produced by space charge due to the primary electrons from the cathode and the secondary electrons from the anode. It has been found however 5 that unless, in the absence of electron emission, the value of

$$\frac{d^2V}{dx^2}$$

is positive to a substantial degree, the space charge is incapable of forming the potential minimum at least in those cases which have so far been investigated, with normal working currents.

In Figure 2 there is shown in dotted lines the distribution of potential *g*₁ when the screen indicated by *C*₁ is closer to the anode. It will be seen that the potential gradient close to the anode is much higher than in the case above considered and consequently a greater additional drop in potential will be required to produce the desired potential minimum. This curve indicates the importance of arranging the anode at a sufficient distance from the screen taking into account the voltages and currents at which the electrodes are to work.

Figure 4 shows the distribution of potential when the anode and screen are at the same potential. Here also

$$\frac{d^2V}{dx^2}$$

30

is positive and therefore a potential minimum is produced even in the absence of electron flow.

This minimum, produced electro-statically when the anode voltage is equal to that of the 35 screen, if it be of sufficient depth, prevents the flow of secondary electrons between the anode and screen in both directions under conditions in which the depression due to space charge alone, owing to high electron velocities, is insufficient. When the anode voltage is much lower than that of the screen, the increase in space charge effects due to reduction in electron velocities causes such an increase in the depression in potential that although there is now no electrostatic potential minimum, there is sufficient total depression of the potential below that of the anode to prevent the flow of secondary electrons 45 from the anode to the screen.

Along a line in a direction at right angles to 50 the direction of the electron stream (that is parallel to the anode surfaces) the distribution of potential in the space between the anode and the screen will of course be such that there is a maximum about midway along the line and low 55 values at the two ends. The potential distribution in the space is thus in the form of a saddle.

The modification of the potential distribution in the anode-screen space produced by the auxiliary electrode has a focusing or concentrating 60 effect upon the electron stream in the screen to anode space. The result of this concentration of the electrons is that the space charge developed is considerably increased and the formation of a potential minimum by space charge is assisted. 65 Thus if secondary electrons are emitted by the anode at a velocity of about 20 volts, for example, they may travel some distance towards the screening grid until they reach a position in which, if the space charge is sufficiently dense, 70 they are brought to rest by the potentials arising from the space charge and the electrostatic field. They then return to the anode and give rise to more secondaries. The process may be repeated so that it may be expected that in the 75

neighbourhood of the anode surface there will be a very dense space charge of comparatively slowly moving electrons. Consequently any algebraic decrease of

$$\frac{dV}{dx}$$

in the neighbourhood of the anode produced by modification of the electrostatic field will be accentuated by the space charge due to the primary electrons and also by the space charge due to the secondary electrons, and the electrostatic and space charge modifications are arranged together to give rise to a combined potential minimum. 15 It is this combined potential minimum which is capable of preventing the flow of secondary electron current from the anode to the screening grid.

For most purposes a tetrode is required to have an anode voltage—anode current characteristic of the kind shown in Figure 5 wherein the anode voltage E_A is shown plotted against anode current I_A for various values of the control grid voltage E_g . It is usually desirable that the knee 20 m should be as sharp as possible and should occur at as low a voltage as possible, and that there should be no inflexion or kink, or at least no marked inflexion, in the characteristic. A kink such as appears at n in the curve $E_g = -4$ and 25 to a less extent in the curve $E_g = -3$ is not material because it is at a point away from any practical working point. However, it has been found possible to produce devices according to this invention in which no noticeable kink is present in 30 any characteristic. A practical load line for a resistive load is shown at o and in the case of an inductive load the load line may have the form shown dotted at o_1 . In neither case do appreciably inflected portions fall within the working 35 range of anode voltages and currents. It will be assumed that the type of characteristic shown in Figure 5 is desired (although it will be understood that for certain purposes other forms of characteristic may be preferred) and certain 40 ways in which departures from the desired characteristic are obtained will be explained in order that the effects of the several variables may be 45 appreciated.

If either the anode d_1, d_2 is too small in area, 50 the auxiliary electrodes e are too close to the electron stream or the projections or slats l extend too far into the electron stream, the characteristic has a knee m of large radius of curvature and the value of anode voltage above which 55 the current is nearly constant is not well defined and rather high. If the area of the anode is increased or if the auxiliary electrodes are arranged further away from the electron stream, the desired form of characteristic can be obtained. 60 Further increase in area of the anode or in the distance of the auxiliary electrodes from the electron stream gives rise to a characteristic in which the knee m is very sharp and the anode current falls beyond the knee and then rises again 65 so that the curve exhibits an inflexion. This form of characteristic indicates that secondary emission is reaching the screening grid.

The way in which the device with what has been referred to as the desired characteristic is believed to operate will now be described.

The screening grid will be assumed to be held at some suitable positive potential relative to the cathode, the auxiliary electrode will be assumed to be at cathode potential and the anode voltage 75 will be regarded in the first place as at cathode

potential. Under these conditions the electrons projected towards the anode will come to rest before reaching the anode on account of the electrostatic field, the low anode potential and the space charge. If the anode voltage be now increased to a value equal to say one half the knee voltage, the space charge will still be sufficient to produce zero potential in the space between the anode and the screening grid. In this region of zero potential all electrons are brought to rest 10 and the region may be regarded as a virtual cathode. The number of electrons flowing from the virtual cathode to the anode or to the screen is determined by the anode potential and the proportion flowing to the anode increases as the 15 anode potential increases.

Above the knee voltage there is still a potential minimum along the electron path but this minimum is no longer zero and any electrons projected by the screening grid towards the anode 20 can only travel forward and eventually strike the anode even though they are retarded by the potential minimum. The knee is sharp because, as the anode voltage is increased, the virtual cathode becomes a region of minimum, but not 25 zero potential, substantially simultaneously over the whole area of the virtual cathode. If the size of the anode is decreased, or if the auxiliary electrodes are placed closer to the stream, the virtual cathode will persist at a greater anode 30 voltage around the edges of the beam than in the centre, thus giving rise to a knee of larger radius of curvature.

If the anode be unduly large, the secondary space charge consisting of electrons moving slowly in random directions can diffuse to the portions of the anode not struck by primary electrons or at least not struck by any considerable number of primary electrons. The space charge is in this case reduced in intensity and 35 may be insufficient to prevent the flow of secondary electrons to the screening grid. Even if the anode is not unduly large it is usually necessary to take steps to prevent the secondary electrons from diffusing around to the back of the anode 40 with similar results to those produced by an unduly large anode. For this purpose the auxiliary electrodes already described are arranged to extend to points close to the edges of the anode. With anodes of small size it may be found unnecessary to extend the auxiliary electrodes so 45 close to the anode.

Unless the anode is of considerably greater length than breadth it is usually desirable to provide the auxiliary electrodes, as already mentioned, close to both pairs of opposite edges. 55 With long and narrow anodes, or where less perfect screening from secondary emission is permissible, it may be sufficient to provide the auxiliary electrodes close to the longer edges of 60 the anode only.

If it is required that the knee voltage should be reduced, it is necessary to reduce the primary space charge so that the virtual cathode formed thereby may collapse at a lower anode voltage. 65 This can be done by increasing the screening grid voltage or by reducing the distance between the anode and the screening grid. The limit to which these two changes can be taken depends, in the case of the former, upon the ability of the 70 primary space charge, with the assistance of the secondary space charge and the electrostatic field, to maintain a sufficiently pronounced potential minimum to prevent the secondary electrons from travelling to the screening grid and, in the 75

latter case, upon the fineness of structure of the screening grid.

It has been found that if the distance between the anode and the screening grid be too small in comparison with the pitch of the screening grid, for example about four times or less, the electron distribution over the surface of the anode is markedly non-uniform. The effect of this is that secondary electrons can return to the screening grid through those parts of the space which lie in front of the screening grid wires because in these parts there is very little primary space charge and consequently only a small screening effect due to space charge.

15 This effect of the non-uniformity of the electron stream can be reduced or removed by dividing the anode into a plurality of parts and preferably by inserting auxiliary electrode plates, which may be connected to the auxiliary electrodes already described, between the two or more parts of the anode.

So far as it has been assumed that the auxiliary electrodes by which the electrostatic potential minimum are produced were maintained at a fixed potential equal to that of the cathode. 25 This is not necessarily the case. In the first place it may be found desirable or convenient to arrange the auxiliary electrodes at fixed potentials differing from the cathode potential. An auxiliary electrode at cathode potential in a given position can often be replaced, with equivalent results, by an auxiliary electrode located closer to the electron stream and having a potential above that of the cathode or by an auxiliary electrode located further from the electron stream and having a potential lower than that of the cathode.

Further it is not necessary that the auxiliary electrode potential should be maintained constant. 40 In some cases the auxiliary electrode potential may be allowed to vary with the potential of the anode or control grid.

In addition to the feature of this invention, namely the provision of means whereby an electrostatic potential minimum can be developed at some region in the space between the screening grid and the anode, at least when these two electrodes are at the same potential, it is usually desirable to arrange that

45 (1) A region between the screening grid and anode which constitutes a virtual cathode at low anode potential should become a region of minimum potential, exceeding zero potential, substantially simultaneously over the greater part of the region as the anode potential is increased, and

(2) The distance between the anode and the screening grid should not be less than about twice the pitch of the screening grid, that is to say the mesh of this grid or the equivalent structure size.

60 Condition (1) is not essential since if it is not fulfilled the principal effect is to influence the shape of the knee of the characteristic. The effect of this may only be that the amplification obtainable is not so free from distortion as with a sharper knee. A knee which is slightly more rounded than it need be may be advantageous in some cases as it has been found possible to obtain a higher impedance above the knee voltage under these conditions.

Instead of allowing the auxiliary electrodes e to extend alongside of the grids and cathode as shown in Figure 1, the auxiliary electrodes may be terminated just short of the screening grid, 75 for example at the inwardly projecting slats l as

shown in Figure 6. The electrostatic field in the space between the anode and screening grid is not affected by this shortening of the auxiliary electrodes. Auxiliary electrodes p, preferably electrically connected to the screening grids c₁ and c₂, may then be provided around the grids and cathode. In the construction shown in Figure 6, the auxiliary electrode is extended around the back of the anode as shown at q.

A modification of the arrangement of Figure 1 is shown in Figure 7 where the projections l are omitted and the auxiliary electrode e is shaped so as to influence the electrostatic field in the anode-screen space in the desired manner. As in Figure 6, the auxiliary electrode is continued behind the anode at q and it also acts as a clamp for the grid and cathode assembly. For this purpose the electrode e is formed in two halves with flanges r which can be bolted or otherwise fixed together, suitable insulating means k₁ being provided between the electrode e and the grids c₁ and c₂.

Another construction according to the invention is shown diagrammatically in Figure 8. In Figure 8, the elongated cathode a is surrounded by a control grid b which is in turn surrounded by a screening grid c. Around the screening grid c is arranged an anode in two sections d₁ and d₂ each of part cylindrical shape and between the anode sections d₁ and d₂ are arranged further part cylindrical electrodes e₁ and e₂ constituting sections of the auxiliary electrode. The two grids b and c are of cylindrical shape and these two electrodes together with the anode and auxiliary electrode preferably extend over substantially the whole length of the cathode a. In this case it will be seen that the sections e₁ and e₂ of the auxiliary electrode constitute continuations of the anode sections d₁ and d₂ and lie in the same cylindrical surface as the anode sections, this surface being coaxial with the cathode a and the two grids b and c. The sections of the auxiliary electrode are connected electrically together and are either connected to the cathode, for example within the envelope f of the device, or else they are brought out to a suitable external terminal by which they can be maintained at a low potential usually not differing greatly from cathode potential.

The auxiliary electrodes e₁ and e₂ serve to 50 modify the electrostatic field in the anode-screen space in such a way that

$$\frac{d^2V}{dx^2}$$

55 is sufficiently positive proceeding from the anode to the screen and when electron current is flowing between the cathode and the anode a space charge is set up in the space as already described. In the regions of the space opposite the rods s which support the grids, however, an electron shadow is cast and in these regions what may be termed the "electron screen" which serves to stop secondary electrons is absent or insufficiently dense. To overcome this difficulty there are provided shield members t which are so placed that they stop secondary electrons which might otherwise reach the screening grid c.

The shields t may be of metal or of insulating material. In the former case they may be of solid metal or in the form of a metal coating on an insulating backing. The metal surface may be connected to the auxiliary electrodes e₁ and e₂ or to some other point of relatively low potential or they may be left unconnected. In the case

where insulating shields are used they may be of glass or mica for example and in operation each shield acquires a charge upon its surface sufficient to make its potential approximately equal 5 to that of the cathode.

In a modification of the arrangement of Figure 8 shown in Figure 9, the anode and auxiliary electrode are still further subdivided into parts d_1 , d_2 , d_3 etc. and e_1 , e_2 , e_3 respectively the former 10 parts being interspersed with the latter.

In Figures 10 and 11 there is shown a modification of the arrangement of Figures 8 and 9, the subdivision being along the length of the cathode. Thus each anode section a_1 , a_2 and 15 each section of the auxiliary electrode e_1 , e_2 , e_3 is in the form of a short cylinder.

Figure 12 illustrates a modification of the arrangement of Figure 8 in which the shields t and the auxiliary electrodes e_1 , e_2 are combined 20 and the whole electrode e_1 , e_2 , t may be regarded as the auxiliary electrode.

In the arrangements of Figures 1, 6, 8, 9 and 10, the auxiliary electrodes are themselves or have parts u (Figures 1 and 6) which form continuations of the anode.

In Figure 12 the auxiliary electrode although not constituting a continuation of the anode surface nevertheless has edges located close to edges of the anode so that the anode sections d_1 and d_2 30 together with the auxiliary electrodes form substantially a box-like structure extending around the grids and the cathode. It will be understood that the auxiliary electrode e of Figures 1, 6 and 7 may extend completely around the anode and 35 grids, that is around the edges thereof parallel to the plane of the paper and this is usually desirable when the anode and grids are of substantially square or circular shape. When these electrodes have a much greater length (in the direction of the length of the cathode) than breadth, however, it is often unnecessary to arrange that 40 the auxiliary electrode completely surrounds the grids and anode.

In discharge devices of the kind described in 45 which the auxiliary electrodes extend close to the edges of the anode, it is often convenient to support the anode from the auxiliary electrodes with the aid of suitable insulators which may be of mica or ceramic material for example. Two ways 50 in which this may be done are illustrated in Figures 18 and 19. Referring to Figure 18, the inner edges of the auxiliary electrodes e_1 and e_2 are slit in such a way that two tongues v_1 and v_2 can be bent outwardly into a horizontal plane near 55 the top of the two auxiliary electrodes. Two similar tongues are also bent out into a horizontal plane near to the bottom of the two auxiliary electrodes but this is not shown in the drawings. The anode d , in the form of a flat rectangular 60 plate, has a rod w preferably of square section fixed along the centre line. Two insulators in the form of rectangular bars of which the upper is shown at x are each provided at their centres with a square hole and have notches cut in their 65 ends. The rod w which projects from the upper and lower ends of the anode is inserted in the holes in the insulators x and the insulators are slipped into position along the auxiliary electrodes, the inner edges of the auxiliary electrodes 70 engaging in the notches in the ends of the insulators. The tongues v_1 and v_2 are then bent outwardly and around the insulators as shown at v_2 to hold them in position.

In a modified construction shown in Figure 19 75 thin strips of insulating material z_1 and z_2 are

fixed to the anode d , for example with the aid of rivets, near to the top and bottom thereof. These strips are arranged to project outwardly beyond the vertical edges of the anode. The anode is placed in position upon tongues v_1 , v_2 , v_3 and v_4 5 bent outward from the plane of the auxiliary electrodes as above described and these tongues are bent over the projecting ends of the strips as shown at v_1 and v_2 to hold them in position.

Instead of bending tongues out from the body 10 of the shields, suitable tongues may of course be fixed to the shields, for example by welding.

The method of assembly above described can also be applied to the securing of a plurality of anode elements to one another in cases, such as 15 have been described above, in which the anode is divided into a plurality of parts. When the anode elements are separated by an auxiliary electrode the adjacent sections of the auxiliary electrode can also be supported from one another 20 by the use of insulators as above described. In a similar way any one electrode can be supported from any other electrode so long as these electrodes have parts extending sufficiently near together.

Referring now to the constructional embodiment of the invention shown in Figures 13 to 17, two control grids b_1 and b_2 and two screening grids c_1 and c_2 are mounted in suitably spaced relation from one another and from the cathode a by 30 means of suitable insulators k . The two control grids are connected together and to a lead l passing through the top of the envelope j . The grids are composed of thin wires extending between supporting rods and between the two upper and between the two lower wires of each grid are passed insulating strips 2 for example of mica. Two anodes d_1 and d_2 are fixed to the mica strips 2 by means of tongues 3 which project through the mica and are bent over. Associated with each anode is an auxiliary electrode composed of a flat portion 4 having a large rectangular aperture, side portions 5 and inwardly projecting portions 6 extending close to the edges of the anode. In the rectangular apertures in 45 the auxiliary electrodes are arranged shields 25 and 26 of channel shape having their edges fixed to the screen grids c_1 and c_2 and therefore electrically connected thereto. The flat portions 5 of the auxiliary electrodes are caused to bear 50 through insulating strips k upon the grid and cathode assembly and the two auxiliary electrodes are then united by metal cross straps 7 , which may be attached by spot welding, and the cathode and grid assembly is thus held firmly 55 in position. Four metal members 8 are then spot welded to the auxiliary electrode and serve to prevent movement of the mica strips 2 .

The shields 25 and 26 may if desired be extended so that together with the screening grid c 60 they completely envelop the control grid b excepting for apertures for the passage of the cathode and control grid leads.

The two anodes d_1 and d_2 and the two control grids b_1 and b_2 may be connected together or if 65 desired they may be brought out to separate terminals so that the device can be used as a push-pull amplifier. The auxiliary electrode structure may be connected to the cathode within the envelope or if desired may be brought out to a 70 separate terminal so that it can be maintained at any desired low potential. The potential of the auxiliary electrode is usually fixed but as already stated need not necessarily be so as it may 75

be caused to vary with the anode potential for example.

Referring to Figures 20-23, there is shown a constructional embodiment of the type of device shown in Figure 8. The electrodes are mounted between two discs of insulating material 9 and 10 for example of mica which have serrated edges adapted to bear against the inner walls of the envelope *f*. The anodes *d*₁ and *d*₂ and auxiliary electrodes *e*₁ and *e*₂ are mounted upon the mica discs 9 and 10 with the aid of lugs 11 which pass through holes in the discs and are bent over. Thus the electrodes *d*₁, *d*₂, *e*₁, *e*₂ serve to form a rigid structure with the discs 9 and 10. The cathode *a* is located in apertures in the centres of the discs 9 and 10 and the grid supporting rods *s* also pass through holes in the discs 9 and 10. The cathode is of the indirectly heated type and the heater is brought out through leads 12 and 13, the cathode itself being connected to lead 14. The anode parts *d*₁ and *d*₂ are connected together by a wire 15 and to a lead 16. The auxiliary electrode parts *e*₁ and *e*₂ are connected together and to shields *t* by a wire 17 and 25 to a lead 18 and also to the cathode *a*. The grids *b* and *c* are connected respectively to leads 19 and 20. The shields *t* are provided in the shadow cast by the rods *s* for the purpose described in connection with Figure 8. These shields are 30 fixed to the mica discs 9 and 10 with the aid of lugs 21.

The anode sections *d*₁ and *d*₂ may be provided as shown with slats or projections 22 in the form of small part annular members of sheet material. These slats are preferably arranged fairly near to the upper and lower end of each section *d*₁ and *d*₂. In one example they are distant from the ends of the sections *d*₁ and *d*₂ by about one fifth the whole length of the sections. The purpose of these slats is to intercept electrons travelling obliquely in the anode-screen space which might in the absence of the slats reach the screen around the outside of the space charge area.

It has been found that in addition to the various factors influencing the behavior of discharge devices according to this invention already mentioned, there are certain other points which should be taken into consideration. If the screening grid be arranged too close to the control grid or be too open, the control grid may produce a reduction in potential in the anode-screen space. This reduction in potential enhances the effect of the auxiliary electrode and must be taken into account when designing the device or else firstly the knee of the characteristic may be of unduly large radius of curvature and secondly the impedance of the device above the knee voltage may be lowered. The former effect is believed to arise because the virtual cathode disappears at different voltages at different points in the anode-screen space. The latter effect is believed to arise from the influence of the control grid in preventing the removal of secondary space charge from the screen by the anode.

In some constructions it is desirable to align the apertures in the control grid with the apertures in the screen in the direction of the electron stream and if a device is designed to operate satisfactorily in accordance with the present invention with aligned grids it may be found to operate unsatisfactorily if the grids are not aligned. The effect produced is equivalent to that

produced by the use of a screen which is too open.

We claim:

1. An electron discharge device comprising, within an evacuated envelope, a cathode surrounded by a control grid, a screening grid surrounding said control grid, an anode having surfaces coextensive with and disposed opposite to longitudinal portions of said screening grid and an auxiliary electrode insulated from said anode and having surfaces coextensive with and disposed opposite to other longitudinal portions of said screening grid, said anode and said auxiliary electrode being each in a plurality of sections, the sections of said anode being interspersed with the sections of said auxiliary electrode.

2. An electron discharge device comprising an elongated cathode surrounded by a control grid, a screening grid surrounding said control grid, an anode having surfaces coextensive with and disposed opposite to longitudinal portions of said screening grid and an auxiliary electrode insulated from said anode and having surfaces coextensive with and disposed opposite to other longitudinal portions of said screening grid, said anode and said auxiliary electrode being each in a plurality of sections, the sections of said anode being interspersed with the sections of said auxiliary electrode, and each of said sections extending over substantially the whole length of said cathode.

3. An electron discharge device comprising, within an evacuated envelope, a cathode surrounded by a control grid, a screening grid surrounding said control grid, an anode having surfaces coextensive with and disposed opposite to other longitudinal portions of said screening grid and an auxiliary electrode insulated from said anode and having surfaces coextensive with and disposed opposite to other longitudinal portions of said screening grid, said anode and said auxiliary electrode being each in a plurality of sections, the sections of said anode being interspersed with the sections of said auxiliary electrode, and each of said sections being of part cylindrical shape and being disposed co-axially with respect to said cathode.

4. An electron discharge device comprising, within an evacuated envelope, a cathode surrounded by a control grid, a screening grid surrounding said control grid, an anode having surfaces coextensive with and disposed opposite to longitudinal portions of said screening grid and an auxiliary electrode insulated from said anode and having surfaces coextensive with and disposed opposite to other longitudinal portions of said screening grid, said anode and said auxiliary electrode being each in a plurality of sections, the sections of said anode being interspersed with the sections of said auxiliary electrode and each of said sections being of part cylindrical shape and being disposed in a single cylindrical surface coaxial with said cathode.

5. An electron discharge device comprising, within an evacuated envelope, a cathode surrounded by a control grid, a screening grid surrounding said control grid, an anode having surfaces coextensive with and disposed opposite to longitudinal portions of said screening grid, an auxiliary electrode insulated from said anode and having surfaces coextensive with and disposed opposite to other longitudinal portions of said screening grid, said anode and said auxiliary electrode being each in a plurality of sections, the sections of said anode being interspersed with

the sections of said auxiliary electrode, and insulating means connected between said anode sections and said auxiliary electrode sections whereby said anode sections are supported by said auxiliary electrode sections.

- 5 6. An electron discharge device comprising, within an evacuated envelope, a cathode surrounded by a control grid, a screening grid surrounding said control grid, an anode surrounding 10 a part of said screening grid and an auxiliary electrode electrically connected to said cathode within the envelope and surrounding another part of said screening grid, said anode and said auxiliary electrode being each in a plurality of sections, the sections of said anode being interspersed with the sections of said auxiliary electrode.

- 15 7. An electron discharge device having, within an evacuated envelope arranged in the order named, a cathode, a control grid, a screening grid and an anode, said anode having a plurality of circumferentially spaced sections, each extending longitudinally over a different part of the space around said cathode, wherein said device 20 also has within said envelope, an auxiliary electrode having an equal number of circumferentially spaced sections which alternate with the anode sections around the cathode and are insulated from said anode sections, said anode sections having their edges disposed close to adjacent edges of said auxiliary electrode sections.

- 25 8. An electron discharge device having, within an evacuated envelope arranged in the order named, a cathode, a control grid, a screening grid and an anode, said anode having a plurality of circumferentially spaced sections, each extending longitudinally over a different part of the space around said cathode, wherein said device 30 also has within said envelope, an auxiliary electrode having an equal number of circumferentially spaced sections which alternate with the anode sections around the cathode and are insulated from said anode sections, said anode sections having their edges disposed close and parallel to adjacent edges of said auxiliary electrode sections.

- 35 9. An electron discharge device having, within an evacuated envelope arranged in the order named, a cathode, a control grid, a screening grid and an anode, said anode extending over a part of the space around said cathode, wherein said device also has within said envelope, an auxiliary electrode extending over a further part of said space and insulated from said anode, said auxiliary electrode having a flat portion disposed close and parallel to a portion of the surface of said anode.

- 40 10. An electron discharge device having, within an evacuated envelope arranged in the order named, a cathode, a control grid, a screening grid and an anode, said anode extending over a part of the space around said cathode, wherein said device also has within said envelope means which form a region of electron shadow in the space 45 between said anode and said screening grid and shield means for substantially preventing the passage of secondary electrons from said anode to said screening grid through said region.

- 45 11. An electron discharge device having, within an evacuated envelope arranged in the order named, a cathode, a control grid, a screening grid and an anode, said anode extending over a part of the space around said cathode, wherein said device also has within said envelope means which form a region of electron shadow in the

space between said anode and said screening grid and conducting shield means for substantially preventing the passage of secondary electrons from said anode to said screening grid through said region.

5

12. An electron discharge device having, within an evacuated envelope arranged in the order named, a cathode, a control grid, a screening grid and an anode, said anode extending over a part of the space around said cathode, wherein said device also has within said envelope means which form a region of electron shadow in the space between said anode and said screening grid and conducting shield means electrically connected to said cathode for substantially preventing the passage of secondary electrons from said anode to said screening grid through said region.

- 17 13. An electron discharge device having, within an evacuated envelope arranged in the order named, a cathode, a control grid, a screening grid and an anode, said anode extending over a part of the space around said cathode, wherein said device also has within said envelope, an auxiliary electrode extending over a further part of said space and insulated from said anode, means which form a region of electron shadow in the space between said anode and said screening grid and shield means for substantially preventing the passage of secondary electrons from said anode to said screening grid through said region.

30

14. An electron discharge device having, within an evacuated envelope arranged in the order named, a cathode, a control grid, a screening grid and an anode, said anode extending over a part of the space around said cathode, wherein said device also has within said envelope, an auxiliary electrode extending over a further part of said space and insulated from said anode, means which form a region of electron shadow in the space between said anode and said screening grid and shield means for substantially preventing the passage of secondary electrons from said anode to said screening grid through said region, said auxiliary electrode and said shield means being connected electrically to said cathode.

35

15. An electron discharge device comprising, within an evacuated envelope, a cathode surrounded by a control grid, a screening grid surrounding said control grid, rods for supporting said control grid and screening grid disposed substantially in a plane, an anode surrounding a part of said screening grid, an auxiliary electrode surrounding a further part of said screening grid and insulated from said anode and shield means disposed between said auxiliary electrode and said screening grid, said anode and said auxiliary electrode being each in two sections, the sections of said auxiliary electrode and said shield being disposed to be intersected by said plane and the sections of said anode lying between the sections of said auxiliary electrode.

40

16. An electron discharge device comprising a cathode, a control grid surrounding the cathode, a screen grid surrounding the control grid, an anode including a plurality of circumferentially spaced sections disposed around the screen grid, and means whereby an electrostatic potential minimum is developed in a region in the space between the screen grid and anode, said means comprising an electrode formed of a plurality of circumferentially spaced sections, each of which is interspersed between a pair of adjacent anode sections.

45

17. An electron discharge device comprising a cathode, a control grid surrounding the cathode,

75

- 5 a screen grid surrounding the control grid, an anode including a plurality of circumferentially spaced sections disposed around the screen grid, and means whereby an electrostatic potential minimum is developed in a region in the space between the screen grid and anode, said means comprising low potential electrodes arranged between adjacent anode sections and outside the space discharge path between cathode and anode.
- 10 18. An electron discharge device comprising a cathode, a control grid surrounding the cathode, a screen grid surrounding the control grid, a plurality of circumferentially spaced members arranged about the cathode and coextensive there with, alternate ones of said members being electrically connected together and constituting the anode electrode, the remaining alternate members being electrically connected together and constituting an auxiliary electrode.
- 15 19. An electron discharge device comprising a cathode, a control grid surrounding the cathode, a screen grid surrounding the control grid, a plurality of circumferentially spaced members arranged about the cathode and coextensive there with, alternate ones of said members being electrically connected together and constituting the anode electrode, the remaining alternate members being electrically connected together and to the cathode and constituting an auxiliary electrode.
- 20 20. An electron discharge device as defined in claim 19 wherein there are provided means which form a region of electron shadow in the space between the anode and the screen grid, and shield means for substantially preventing the passage of secondary electrons from the anode to the screen grid through said region, said shield means being electrically connected to both the cathode and to the auxiliary electrode.
- 25 21. An electron discharge device including an evacuated envelope and having arranged in the order named within the envelope, a cathode, a control grid, a screen grid, and an anode, said

screening grid and anode being spaced from each other to provide during operation of said electron discharge device a space charge between said screening grid and anode, said control grid and screening grid being provided with side rods 5 lying in a common plane, said side rods forming a region of electron shadow in the space between said anode and said screening grid, and shield means for substantially preventing the passage of secondary electrons from said anode to said screening grid through said region.

22. An electron discharge device including an evacuated envelope having within the envelope and arranged in the order named a cathode, a control grid, a screening grid and an anode, said 15 screening grid and anode being spaced from each other to provide during operation of the tube a space charge between said anode and said cathode, said control grid and screening grid having side rods lying in a common plane, said side rods 20 forming a region of electron shadow in the space between said anode and said screening grid, and a conducting shield means for substantially preventing passage of secondary electrons from said anode to said screening grid through said region. 25

23. An electron discharge device having an evacuated envelope containing in the order named a cathode, a control grid, a screening grid, and anode, said screening grid and anode being spaced 30 to provide during operation of the device a space charge between said screening grid and anode, said control grid and screening grid having side rods lying in a common plane, said side rods forming a region of electron shadow in the space between said anode and said screening grid, and 35 conducting shield means electrically connected to said cathode for substantially preventing passage of secondary electrons from said anode to said screening grid through said region.
